UNITED STATES PATENT OFFICE.

TOWNSEND PALMER, OF MIDDLETOWN, CONNECTICUT, ASSIGNOR TO THE I. E. PALMER COMPANY, OF MIDDLETOWN, CONNECTICUT, A CORPORATION OF CONNECTICUT.

CANOPY.

1,214,480.

Specification of Letters Patent. Patented Jan. 30, 1917.

Application filed November 3, 1915. Serial No. 59,491.

To all whom it may concern:

Be it known that I, TOWNSEND PALMER, a citizen of the United States, and a resident of Middletown, in the county of Middlesex, 5 and State of Connecticut, have invented an Improvement in Canopies, of which the following description, in connection with the accompanying drawings, is a specification, like characters on the drawings representing 10 like parts.

This invention relates to canopies of general construction and to frames therefor, the canopy being adapted for use in connection with beds, hammocks of various descriptions 15 and other supports in other relations.

In order that the principle of the invention may be readily understood, I have disclosed a single embodiment thereof in the accompanying drawings, wherein—

20 Figure 1 is a plan view of the central portion of a canopy frame embodying my invention; Fig. 2 is a central vertical section of the construction shown in Fig. 1, the canopy rods being indicated in operative 25 position in full lines and in storage position in dotted lines; Fig. 3 is an inverted plan view of the frame shown in Fig. 1; Fig. 4 is a plan view of the complete canopy; and Fig. 5 is a side elevation of the structure 30 shown in Fig. 4.

An important object of my invention is to provide a canopy and canopy frame for general use which are comparatively simple in construction and therefore may be readily 35 and inexpensively manufactured.

Other objects of the invention will be set forth more fully hereinafter.

Referring more particularly to the drawings, I have therein represented a central 40 or body member 1, which may be of any suitable material, but preferably is metallic and desirably is cast. Said central or body member is preferably formed as a series of radiating, longitudinally channeled parts 2 extending from the head 3, said central or body member being thus of a general spider form. I have herein represented six radiating parts, but any suitable number may, of course, be employed. The head 3 is adapted 45 to receive a canopy-supporting device and preferably for that purpose it is provided with a central opening 4 to receive the threaded portion 5 of a supporting hook 6. Preferably the head 3 is of relatively thin

metal, so that it may act as a nut to receive 55 the threaded portion of the hook 6, thereby permitting the latter to be adjustably positioned therein. I have herein represented the hook as having a flange 7, and if desired a suitable washer 8 may be interposed 60 between the upper surface of the head 3 and the flange 7. The channels of the radiating parts 2 are indicated most clearly at 9 in Fig. 2. These may be of any suitable depth and extent, but preferably they merge into 65 each other at the head 3, the screw-threaded portion 5 of the supporting hook 6 being positioned at the meeting point of the several channels.

I provide any suitable number of supporting rods, the number employed corresponding to the number of radiating parts 6. The said rods are herein indicated at 10, 11, 12, 13, 14, 15 in the several figures. The relative length of these rods may, of course, 75 be varied in accordance with the shape of the frame and the intended use thereof. In that form of the invention herein shown, I have represented the cross rods 10 and 13 as shorter than the diagonally arranged 80 rods 11, 12, 14, 15.

Surrounding the central or body member and its radiating parts, I provide a ring 16 which is received upon the ends of the radiating parts 2, and for this purpose I preferably slightly recess the ends of the latter in the horizontal plane of said ring, as indicated at 17 in Fig. 2. As shown most clearly at 18 in Fig. 1, I extend one of the walls of the channel of each radiating part 2 outward beyond the other wall thereof, thus in a simple manner preventing displacement of the ring 16. Obviously, however, my invention is not limited to the construction shown in positioning the ring 85 16. Each of the rods 10 to 15 is provided with a portion 19 bent through substantially 180 degrees and positioned in the end of each channeled part 2, being confined therein by the ring 16 in such manner as to permit the ready pivotal movement of said rods into either of the positions shown in Fig. 2. Preferably I provide the outer terminal portion of each part 2 with a housing 19' within which and the ring 16 the arched or 95 pivotal portions of said rods are positioned. Each of said rods is provided with an inner terminal portion 20, preferably of slightly 100 105

less length than the channel of the part 2 in which it is received, the construction being such that when the rods are rocked into the horizontal position assumed in use, the 5 ends 20 are housed within said channels.

Any suitable textile or other flexible material may be employed in connection with the canopy frame. I have herein indicated the use of mosquito or other netting at 21 10 in Figs. 4 and 5. The said netting may be secured in the frame in any suitable manner. Preferably the hook 6 is passed through the netting at the central or body portion 1, and preferably each of the single rods is provided with a hooked end 22 to which the 15 netting may be secured in any suitable manner.

It will be evident from the foregoing description that the canopy frame is composed 20 of substantially a minimum of parts and yet is of strong and extremely serviceable construction. The frame may be readily folded into condition for storage or transportation by rocking the rods into the position indicated in dotted lines in Fig. 2, the 25 said rods being brought into substantial parallelism. The netting may be readily wrapped or folded about the frame with the rods in the position shown in Fig. 2.

Having thus described one illustrative embodiment of my invention, I desire it to be understood that although specific terms are employed, they are used in a generic and descriptive sense and not for purposes of 35 limitation, the scope of the invention being set forth in the following claims.

Claims:

1. A canopy frame having a central or body member, a supporting ring and a series of rods pivotally mounted upon said ring between their ends, each of said rods having an inner end extending a substantial distance inward beyond the pivotal point 40

thereof and adapted to bear against the under side of said central or body member. 45

2. A canopy frame having a central or body member, a supporting ring carried thereby and a series of rods pivotally mounted upon said ring between their ends, each of said rods having an inner end extending 50 a substantial distance radially inward beyond the pivotal point thereof, and having a bearing relation with respect to said member.

3. A canopy frame having a central or 55 body member provided with a series of substantially radial channels, a ring encircling said central or body member, and a series of rods corresponding in number to said channels and pivotally mounted upon said ring, the inner ends of said rods being received in said channels when the rods are 60 radially extended.

4. A canopy frame having a central or body member having a series of substantially radial channels provided with housings at their outer ends, a corresponding series of rods pivotally mounted at the outer ends of said housings, and a surrounding ring to support said rods in said housings 65 70 at said point, the inner ends of said rods being received in said channels when the rods are radially extended.

5. Means for supporting a canopy consisting of a canopy frame adapted to be 75 positioned at the top of a canopy and having a central or body member 1 provided with radial channels 2, and a marginal ring 16, a series of rods pivotally mounted between their ends upon said ring and having inner ends 20 extending radially inward beyond the pivotal point of said rods and adapted to enter said channels 2. 80

In testimony whereof, I have signed my name to this specification.

TOWNSEND PALMER.
